UNITED STATES PATENT OFFICE.

GEORGE F. MURDOCK, OF WELLSVILLE, OHIO.

DESIGN FOR A SHINGLE.

SPECIFICATION forming part of Design No. 35,592, dated January 21, 1902.

Application filed December 6, 1901. Serial No. 84,972. Term of patent 7 years.

To all whom it may concern:

Be it known that I, GEORGE F. MURDOCK, a citizen of the United States, and a resident of Wellsville, in the county of Columbiana and State of Ohio, have invented and produced a new and original Design for a Shingle, of which the following is a specification, reference being had to the accompanying drawings, forming a part thereof, in which—

10 Figure 1 is a plan view of a shingle embodying the features of my design, and Fig. 2 is a longitudinal edge view thereof.

15 The leading feature of the design consists in the shield-like formation of one end portion of the shingle.

The minor features of the design consist in the oppositely-located curved depressions *a*, occurring in the longitudinal edges of the shingle, the inwardly-curved lines *b* at each

side of the central portion of the shield-like 20 end of the shingle, which lines meet at the center of said shingle end, forming an angular point *c*, and in the lines *d*, which connect the depressed surfaces *a* with the marginal end lines *b*. 25

Having thus described my invention, I claim as new and desire to secure by Letters Patent—

20 The design for the shingle herein shown and described.

30 In testimony whereof I have signed my name to this specification in the presence of two subscribing witnesses.

GEORGE F. MURDOCK.

Witnesses:

WILLIAM F. LOVES,
WILLIAM H. BURGESS.
